Des 1010

CRESSON, STEWART & PETERSON.

Patented June 1. 1858.

FIG. 2.

FIG. 3.

Office

Dec. 1010

✓ *E. J. Delany & J. Martino, of Philadelphia Pa.*
Assignors to

W. P. Cresson, D. Stewart & R. Peterson, of same place.

Letters Patent No. 1010. Dated June 1, 1858.

The schedule referred to in these Letters Patent and making part of the same.

To all whom it may concern:

*Be it known that we Edw. J. Delany and
John Martino, both of the City of Philadelphia and State of Pennsylvania,*

have invented or produced a new and original design for plates of a cooking stove, and we do hereby declare that the following is a full and exact description of the same reference being had to the accompanying drawing and to the letters of reference marked thereon.

Our design refers to the ornamental figures and forms on the front plate, and two side plates of a cook stove which we call the "magic shield". On reference to the accompanying drawing, which forms a part of this specification,

Fig. 1 is a perspective view of the Magic Shield, cooking stove.

Fig. 2, a view of the front plate with its doors.

Fig. 3, a view of the side plate with its doors.

The front plate A, is furnished with the ornamental door, a, which covers the opening, through which air may be admitted to the fire place above the fuel. Two doors, b, and, b', ornamented with peculiar devices, are hinged to the front plate, in front of the grating of the fire place. B, is the side plate with denticulated moldings on the edge, and having a permanent panel, d, with ornamental figures on an oven door, e, with foliage in bas-relief. Both the panel, d, and oven door, e, are surrounded with denticulated moldings.

We claim the combination and arrangement of ornamental figures and forms, represented in and by the accompanying drawing, as forming together an ornamental design for the front and two sides of a cooking stove.

In testimony whereof we have signed our names to this specification before two subscribing witnesses.
